UNITED STATES PATENT OFFICE.

ENGELBERT GERSPACHER, OF VIENNA, AUSTRIA-HUNGARY.

PENCIL-HOLDER WITH ADJUSTABLE CORE.

1,043,518.

Specification of Letters Patent.

Patented Nov. 5, 1912.

Application filed January 16, 1911. Serial No. 602,889.

To all whom it may concern:

Be it known that I, ENGELBERT GERSPACHER, a subject of the Emperor of Austria-Hungary, and resident of VI Stumpergasse 23, Vienna, Austria-Hungary, have invented certain new and useful Improvements in Pencil-Holders with Adjustable Cores, of which the following is a specification.

10 Heretofore pencil holders with adjustable cores have been made where the core is yieldingly supported and where the shell is arranged movably in a corresponding bore of the holder. With these holders, a piece of 15 wire is used to support the core and the arrangement of the wire in the holder is effected in such a way that the exchange of the core is complicated, since the said wire piece must be taken out, together with the core, 20 in order to effect the said exchange and must be inserted together with the new core, and with the core shell, into the holder.

According to the present invention the support of the core is effected by means of 25 a yielding piece of sheet metal wire or string inserted into the holder diametrically to the longitudinal axis of the same and near to its outer end, the whole arrangement being effected in such a way that the 30 exchange of the core is produced by simply pulling out the core shell, inserting into the same a new core and replacing the shell into the holder.

With the holders of this class the elasticity 35 of the support is obtained by means of a spring arranged upon the end of the holder and hence the exchange of the spring, in case of emergency, becomes very difficult without impairment of the holder, since access to the spring, with ordinary tools, is 40 practically impossible. As, according to the present invention, the spring is arranged near to the free end of the holder, and renewal may be easily effected.

45 Figure 1 is a view in side elevation of a pencil embodying my invention, parts being shown in longitudinal central section to disclose details of construction. Fig. 2 is a view similar to Fig. 1 showing a modification 50 of my invention. Fig. 3 is a fragmentary view of the core end of a pencil, a modification of my invention, parts being shown in longitudinal, central section to disclose details of construction. Fig. 4 is an 55 end view of the device shown in Fig. 3. Fig. 5 is a view similar to Fig. 3 showing a

further modification of my invention. Fig. 6 is a view similar to Fig. 5 showing a still further modification of my invention. Fig. 7 shows a view of the core shell. Fig. 8 shows a modification of the spring illustrated in Fig. 5 and Fig. 9 shows a bush in side and end views respectively for fixing the spring in the holder.

A is the holder having a bore a. The shell 65 B is inserted onto the holder A. C is the core and D is an additional tubular holder piece with bottom b. The core shell B is provided with two oppositely disposed grooves c c' which are open to the slot d 70 and extend longitudinally through the head piece e for the reception of the core C.

Near to the free end of the holder an elastic piece of wire is drawn through holes f, the wire being preferably bent in its central part, as shown in the drawing, and the size of the wire being chosen so that it fits into the longitudinal slots d. The core shell is moved into the bore and the wire acts as an abutment of the core. It will be readily 80 seen that every inward movement of the core shell causes the core to move outwardly from the head piece e. The said wire may be replaced by a strong cord of india rubber or the like without altering the effect. Instead 85 of the wire I may also use a piece of sheet metal g (Figs. 2 and 4) inserted into axial slots h (Fig. 4) or into saw cuts (Fig. 3) preferably with the flat portion of the sheet metal piece lying against the sides of the 90 slots d. The thickness of this sheet metal piece corresponds to the slot d. In order to obtain a quick outward movement of the core, by the said sheet metal piece, the latter is made of hardened steel and is provided 95 with a perforation i (Fig. 4) in such a manner that a narrow cross piece is left against which abuts the core of the holder, this cross piece having sufficient elasticity to effect 100 outward movement of the core.

In order to increase the elasticity of the inserted piece of wire and also to facilitate the fixture of this piece into the holder it is preferably to employ a piece of wire which is bent several times in opposite directions, 105 snakelike, one shank abutting against a projecting surface of the holder and the other shank abutting against the core. Thereby the degree of elasticity of the core support is considerably increased. The introduction 110 and the exchange of the spring is effected in a simple way either with the aid of a

lateral slot in the holder or with aid of a short additional piece provided with a slot for the spring and inserted into a corresponding bore of the holder.

- 5 In Fig. 5 a core holder is shown, the elastic support of the core being effected by means of a relatively flat spring bent alternately in opposite directions. Near the free end of the holder the bore α is turned out to a 10 somewhat larger diameter to accommodate a bush E (Fig. 9) slotted in its upper part and serving for taking a spring, bent in opposite directions. The bush E together with the spring is inserted into the holder A the 15 spring resting with its upper part against the bottom of the bush excavation and resting with its lower part against a flange of the bush E the intermediate parts of the spring resting within the slot of the bush E.
- 20 The bushing E is shifted into the bore of the bush in such a way that the spring enters also the axial and corresponding slots of the core shell B. The core C abuts against the shanks of the springs and moves outwardly 25 after shifting back the core shell into the holder.

In case of the core not projecting outwardly from the shell the desired distance it will be sufficient to press the head piece e of the 30 shell against any rigid surface in order to tension the spring of the latter causing therefore the outward movement of the core after release of the pressure upon the head piece e. The additional bush piece E may 35 also be dispensed with and the slot h for taking up the spring may be provided in the holder (Fig. 6) the spring ends abutting against the lower and upper walls respectively of the slot. The spring may also be 40 shaped in such a way that its upper shank projects centrally and longitudinally in the direction of the core (Fig. 8). The lower end of such a spring abuts against the wall of the slot and the longitudinal projection 45 of the spring is carried through the central groove of the core shell B and abuts against the core itself.

Having now described the nature of my invention and in what manner the same is 50 to be performed what I claim is:—

1. A pencil comprising in combination, a body portion, a shell carried by said body

portion, a core carried by said shell, the said shell being movable with respect to said body portion and the said core being movable 55 with respect to said shell, and means carried by said body portion forming a yieldable abutment for said core.

2. A pencil comprising in combination, a body portion provided with a longitudinally 60 extending bore, a core, a shell adapted for insertion into said bore and having grooves adapted to retain said core, and yieldable means carried by said body portion adjacent the mouth of the said core in the latter, 65 adapted to form a yieldable abutment for the core in said shell.

3. In a pencil of the character described, the combination of a core, a shell therefor, a holder adapted to receive said shell and provided with recessed portions, the said core, shell, and holder being movable with respect to each other, and a relatively flat spring bent alternately in opposite directions carried by said recessed portion of said holder 75 and disposed with its plane in the line of movement of said core, the spring forming a yieldable abutment for the latter.

4. A pencil comprising in combination, a body portion provided with a longitudinally 80 extending bore and a second bore of larger diameter at the end of said body portion and opening into said first mentioned bore, a bush adapted to be inserted into the larger of said bores of said body portion and provided with a bore adapted to register with said first mentioned bore of said body portion, said bush having oppositely disposed slots disposed laterally of the bore therein, a core, a shell provided with a bore for said 90 core and having slots disposed laterally of the said bore in said shell, said shell being adapted for insertion into the said bore of said bush and first mentioned bore of said body portion, and a relatively flat spring 95 disposed within said slots of said bush and shell forming a yieldable abutment for the said core.

In testimony whereof I affix my signature in presence of two witnesses.

ENGELBERT GERSPACHER.
